DESIGN FOR AN ARTICLE FOR SMOKING TOBACCO

William F. Pfau, Cincinnati, Ohio

Application October 31, 1934, Serial No. 53,830

Term of patent 3½ years

To all whom it may concern:

Be it known that I, William F. Pfau, a citizen of the United States, residing at Cincinnati, in the county of Hamilton and State of Ohio, have invented a new, original, and ornamental Design for an Article for Smoking Tobacco, of which the following is a specification, reference being had to the accompanying drawings, forming part thereof.

I claim:

The ornamental design for an article for smoking tobacco substantially as shown.

WILLIAM F. PFAU.
